R. F. GOWEN.
COIL MOUNTING.
APPLICATION FILED JULY 23, 1920.

Patented Nov. 29, 1921.

Inventor
Robert F. Gowen
by his attorney, Daniel E. Darby

UNITED STATES PATENT OFFICE.

ROBERT F. GOWEN, OF NEW YORK, N. Y., ASSIGNOR TO DE FOREST RADIO TELEPHONE AND TELEGRAPH COMPANY, OF NEW YORK, N. Y., A CORPORATION OF DELAWARE.

COIL-MOUNTING.

1,398,372.

Specification of Letters Patent. Patented Nov. 29, 1921.

Application filed July 23, 1920. Serial No. 398,521.

To all whom it may concern:

Be it known that I, ROBERT F. GOWEN, a citizen of the United States, residing at New York, county of Westchester, and State of New York, have made a certain new and useful Invention in Coil-Mountings, of which the following is a specification.

This invention relates to coil mounts, and is especially adapted for use in connection 10 with inductance coils such as are commonly employed in the radio art.

The object of the invention is to provide a coil mount which is simple in structure, efficient for its purpose, and economical 15 of manufacture.

A further object of the invention is to provide a coil mount which is specially adapted for use in connection with the honeycomb and duo lateral types of coils 20 now in common use in the radio industry.

Further objects of the invention will appear more fully hereinafter.

The invention consists substantially in the construction, combination, location and 25 relative arrangement of parts, all as will be more fully hereinafter set forth as shown by the accompanying drawing and finally pointed out in the appended claims.

Referring to the drawing,—

Figure 1 is a view in side elevation of a coil mounting embodying my invention.

Fig. 2 is a view in perspective of the same.

Fig. 3 is a view in perspective with the 35 parts partially detached.

The same part is designated by the same reference numeral wherever it occurs throughout the several views.

In my copending application, Serial No. 40 287,397, filed April 4, 1919, for self supporting inductance coils, I have shown and described what has become known in the radio art as the honeycomb type of inductance coil, and in one modification thereof as the 45 duo lateral type of inductance coil; also in my co-pending application, Serial No. 318,631, filed August 20, 1919, for inductance coil mounting, I have shown arrangements of support for use of these coils as inductance 50 coils in the radio art where the coils are used for loose coupling of the respective electric circuits in which they are employed. In my last above identified application I have shown the particular type of 55 mounting for the coil which forms the sub-

ject matter of my present application as is illustrated in the drawing forming part hereof wherein the coil 1 is circular in shape with a circular opening therethrough. In the form shown the coil is formed of a 60 single wire wound upon a base 2 of non-conducting material such as cardboard or the like. The wire is wound upon the base at a constant pitch. When the opposite edge of the coil is reached the direction of 65 the wire is reversed, but the pitch remains the same, so that this layer of the wire runs in an opposite direction, but at the same pitch. The layers are thus built up one upon the other until the required height is 70 reached according to the specifications of the coil employed as to inductance therein, etc., and the unit thus constructed is coated in the usual manner with a substance which binds the coil thus built up into a rigid 75 unit such as a self-supporting coil, with the ends 3 and 4 of the wire extending therefrom for the purpose of being connected to the terminals, which will be more fully hereinafter described. While I have shown 80 and described the coil as of the honeycomb or inductance or duo lateral type, I do not desire to be limited or restricted thereto as it is obvious that the mounting of my invention may be equally well applied to 85 any form of circular coil. If desired, and as shown, in addition to the coating which acts toward keeping the coil in a self-supporting unit a tape 5 may be wound around the coil, and preferably at the point where 90 the ends thereof protrude therefrom to thereby retain the ends of the wire in the proper position relative to the coil. I provide a block of insulating material of any suitable shape or size indicated at 6 in 95 which are located to extend therethrough a plug 7 and a jack 8. The plug and jack method of forming electrical contact is the method now most generally in use, and though therefore I have illustrated 100 this type of electrical circuit connection I do not desire to be limited or restricted in this respect. The ends 3 and 4 of the wire are suitably connected, for example, soldered, to the ends of the plug and 105 jack 7 and 8 in the usual well known manner. The opposite sides of the block member 6 have holes therein adapted to register with threaded borings through the plug and jack respectively. A strap 10 is then 110

fastened to the opposite sides of the block 6, and secured thereto by means of a metal plate 11, held by means of screws inserted through the plate, and extending in the 5 holes in the block, and the plug and jack respectively, to thereby clamp the free ends of the strap against the respective top and bottom surfaces of the block. From the foregoing it will be seen that I have provided 10 an exceedingly simple and efficient mounting for a coil of the circular type, the strap 11 holding the coil rigid relative to the block 6 with no strain imposed upon the ends 3 and 4 of the wire and enabling in 15 a coil of this type a handy convenient unit adapted to be plugged into or otherwise electrically connected to the terminals of a circuit in which the coil is to be included. Where a honeycomb type of coil is employed, or in fact in any instances where it is desired to utilize the surrounding air for affecting the capacity of the coil, the strap 11 may be provided with a number of perforations or orifices therethrough throughout 20 its length.

Many modifications and changes in detail will readily occur to those skilled in the art without departing from the spirit and scope of my invention as defined in the claims.

30 Therefore what I claim as new and useful and of my own invention and desire to secure by Letters Patent is,—

1. The combination with a wire coil having wire terminals, of a block of insulating material having electrical terminals therein connected to said wire terminals, and a strap extending around the outer surface of said coil, and secured at its ends to said block.

40 2. The combination with a wire coil having wire terminals, of a block of insulating material having plug and jack terminals therein connected to said wire terminals, and a strap extending around the outer surface of said coil and secured at its ends to said block.

3. The combination with a wire coil having wire terminals, of a block of insulating material having electrical terminals therein connected to said wire terminals, and a strap of non-conducting material extending around the outer surface of said coil and secured at its ends to said block.

4. The combination with a wire coil having wire terminals, of a block of insulating material having plug and jack terminals therein connected to said wire terminals, and a strap of non-conducting material extending around the outer surface of said coil and secured at its ends to said block.

5. The combination with a wire coil having wire terminals, of a block of insulating material having electrical terminals therein connected to said wire terminals, and a strap 65 extending around the outer surface of said

coil, and secured at its ends to said block, said strap being provided with perforations to permit the passage of air therethrough.

6. The combination with a wire coil having wire terminals, of a block of insulating material having plug and jack terminals therein connected to said wire terminals, and a strap extending around the outer surface of said coil and secured at its ends to 70 said block, said strap being provided with perforations to permit the passage of air therethrough.

7. The combination with a wire coil having wire terminals, of a block of insulating material having electrical terminals therein connected to said wire terminals, and a strap of non-conducting material extending around the outer surface of said coil and secured at its ends to said block, said strap 80 being provided with perforations to permit the passage of air therethrough.

8. The combination with a wire coil having wire terminals, of a block of insulating material having plug and jack terminals 90 therein connected to said wire terminals, and a strap of non-conducting material extending around the outer surface of said coil and secured at its ends to said block, said strap being provided with perforations 95 to permit the passage of air therethrough.

9. The combination with a wire coil having wire terminals, of a block of insulating material having electrical terminals therein connected to said wire terminals, and a strap extending around the outer surface of said coil, clamping plates, and means for clamping the free ends of said strap between said plates and said block.

10. The combination with a wire coil having wire terminals, of a block of insulating material having electrical terminals therein connected to said wire terminals, and a strap extending around the outer surface of said coil, clamping plates positioned over 11 the free ends of said strap, and screws extending through said plates into said block for securing said strap and plates thereto.

11. The combination with a wire coil having wire terminals, of a block of insulating material having plug and jack terminals therein connected to said wire terminals, and a strap extending around the outer surface of said coil, clamping plates positioned over the free ends of said strap, and 11 screws extending through said plates into said block for securing said strap and plates thereto.

12. The combination with a wire coil having wire terminals, of a block of insulating material having plug and jack terminals therein connected to said wire terminals, and a strap extending around the outer surface of said coil, clamping plates positioned over the free ends of said strap, and screws 1150

extending through said plates into said block and said plug and jack terminals, respectively, for securing said strap, plates and terminals to said block.

5 13. The combination with a wire coil having wire terminals, of a block of insulating material having plug and jack terminals therein connected to said wire terminals, and a strap extending around the outer

surface of said coil, and means extending into said block and said plug and jack for securing the ends of said strap to said block.

In testimony whereof I have hereunto set my hand on this 19th day of July A. D., 15 1920.

ROBERT F. GOWEN.
